UNITED STATES PATENT OFFICE.

FRANCIS H. TREAT, OF CHICAGO, ILLINOIS, ASSIGNOR TO THE ILLINOIS STEEL COMPANY, OF SAME PLACE.

APPARATUS FOR STAMPING BILLETS.

SPECIFICATION forming part of Letters Patent No. 445,291, dated January 27, 1891.

Application filed August 16, 1890. Serial No. 362,200. (No model.)

To all whom it may concern:

Be it known that I, FRANCIS H. TREAT, of Chicago, Cook county, Illinois, have invented a new and useful Improvement in Apparatus 5 for Stamping Billets, of which the following is a specification.

The object of my invention is to provide for stamping numbers, letters, or characters into hot blooms, billets, or metal bars as they 10 are traveling to their place of delivery; and the invention consists in the features and combinations hereinafter described and claimed.

In the accompanying drawings, Figure 1 is a broken side elevation of my improved 15 stamping-machine; Fig. 2, a plan view of the same, and Fig. 3 a sectional view taken in line 3 of Fig. 1.

A is an I-beam, forming the base or support of the machine, and also forming a track 20 for the conveyer; B, the conveyer; C, a billet traveling on the conveyer; D, side rails or guards; E, stationary revoluble rollers having their bearings in the side rails; F, cross-arms pivotally connected at one end to a stud 25 f, secured to the side rail or guide D, its other end being flexibly connected to said side rail; G, a shaft mounted on the cross-arms, and g a hand-wheel on the shaft for turning the same; H, a stamping-head on the shaft 30 adapted to be rotated or oscillated by means of the hand-wheel to bring it into contact with the billet; h, dies in the stamping-head adapted to be forced into the billet by the rotation of the shaft, and h' set-screws for securing the dies in the stamping-head.

In the manufacture of billets of steel it is generally desirable to keep a record of each heat, and as the billets are generally sold by chemical specification it is also desirable that the 45 billets be so stamped or marked as to indicate the heat from which they come. For instance, if all the billets of a given heat be stamped or marked 100 and a chemical record is kept of this heat it will of course be apparent that 50 any billet bearing the mark 100 is of the chemical composition shown by such record. This stamping or marking of the billets is of course most easily done while they are hot; and the object of my invention is to provide 55 for stamping them as soon as formed, and

preferably while they are being conveyed to a place of delivery.

My improved stamping-machine consists, essentially, of a segmental roller mounted on a horizontal shaft adapted to be rotated by a 55 hand-wheel or otherwise, the roller being provided with a suitable die or dies to form the figure, letter, or character desired to be cut or impressed on the billet.

I am not aware that any marking or stamping machine has ever been heretofore used in connection with a conveyer having traveling rollers, and so one feature of my invention may be considered as consisting in providing a stamping or marking machine for 65 such a conveyer.

As the billet which is being carried forward on the conveyer comes under the segmental roller, the operator, by turning the hand-wheel, causes the part containing the die or 70 dies to revolve forward, and this forces the die down in the billet to the extent necessary for marking purposes. Of course the proportion and arrangement of the parts are such that the die will be required to cut into the 75 billet, but not farther than necessary to plainly mark it.

The segmental roller may be provided with a single die or with any number of dies desired, each die being of course adapted to cut 80 a single figure, letter, or character. For instance, if it be desired to mark the billet 9 the segmental roller will only be required to have a die adapted to cut this one figure into the billet, while if it be desired to mark the billet 85 927 the segmental roller will be required to have three dies, the first adapted to cut figure 9, the second figure 2, and the third figure 7. These dies are preferably capable of being put into the segmental roller or taken 90 out therefrom at will, being inserted in sockets in the roller and held in place by a set-screw.

If the segmental roller were alone, it is apparent that if it should strike down upon the 95 end of a billet it might cause the end to be depressed and the billet thus put out of position for marking. This would be particularly the case if the billets were being carried on a conveyer having traveling rollers. To avoid 100

this result, depressing one end and thus getting the billet out of position for marking, I provide an additional roller or rollers in front or rear of the segmental roller, or both in front 45 and rear, which additional rollers are so placed as to allow the billet to just pass under them, and thus to hold them steadily down upon the traveling rollers of the conveyer. The billets, being thus held down by the rollers in front or rear of the segmental roller, cannot of course tip up or down when fulcrumed on one of the traveling rollers not directly under the segmental roller.

As safeguards to the machine, I provide 15 springs to receive and regulate the strain in case the billet should be slightly deformed by the shearing or otherwise. The construction and operation of these springs will be apparent from the drawings.

20 The cross-arms being pivotally secured at one end and flexibly secured at the other form a flexible and adjustable bearing for the shaft carrying the segmental roller. The pivotal connection is formed by means of an upwardly-projecting lug and the flexible connection by means of a spring above the arm and on the stud, which is secured to the side rail and passes up through the end of the arm. The adjustment of the arms is effected 25 through the nuts and screws on said upwardly-projecting stud.

It will be understood that I use the term 30 "billet" in a general sense, and as meaning a billet, bloom, or other piece of metal desired to be marked or stamped, and that in the same way I use the term "conveyer" as meaning, generally, either stationary or traveling rollers or other means employed for advancing the heated metal to a place of delivery.

I claim—

1. In combination with a billet-conveyer having traveling rollers, a stamping-machine

above the conveyer to mark the billets while in their course of travel, substantially as described. 45

2. In combination with a billet-conveyer, a roller placed above the conveyer, having marking-dies secured therein, and means for operating the roller to bring the dies into contact with the billet, substantially as described. 50

3. In combination with a billet-conveyer, a segmental roller having marking-dies secured therein mounted in adjustable bearings, and means for operating the segmental roller to bring the marking-dies into contact with the billet, substantially as described. 55

4. In combination with a billet-conveyer, a segmental roller having marking-dies secured therein mounted in flexible and adjustable bearings, and a hand-wheel for operating the roller to bring the marking-dies in contact with the billet, substantially as described. 60

5. In combination with a billet-conveyer, a segmental roller having marking-dies secured therein, a plain roller in front and rear of the segmental roller, and means for operating the segmental roller to bring the marking-dies into contact with the billet, substantially as described. 65

70 6. In combination with a billet-conveyer, a stamping-machine above the conveyer, comprising frame-work, a roller having marking-dies secured therein mounted in the frame-work, a plain roller or rollers in front and rear of the segmental roller, and springs pressing upon the frame-work to hold the same in position and permit of its yielding when subjected to undue strain, substantially as described.

FRANCIS H. TREAT.
